UNITED STATES PATENT OFFICE.

AUGIE L. HANSEN, OF CHICAGO, ILLINOIS, ASSIGNOR TO JUSTRITE MANUFACTURING COMPANY, OF CHICAGO, ILLINOIS, A CORPORATION OF ILLINOIS.

DESIGN FOR A FIRE-EXTINGUISHER BODY.

46,771.

Specification for Design.

Patented Dec. 15, 1914.

Application filed August 10, 1914. Serial No. 856,143. Term of patent 7 years.

To all whom it may concern:

Be it known that I, AUGIE L. HANSEN, a citizen of the United States, and a resident of Chicago, in the county of Cook and State of Illinois, have invented a new, original, and ornamental Design for a Fire-Extinguisher Body, of which the following is a specification, reference being had to the accompanying drawing, forming part thereof.

Figure 1 is a plan view showing my new design, and Fig. 2 is a side view.

I claim:

The ornamental design for a fire extinguisher body, as shown.

AUGIE L. HANSEN.

Witnesses:

CHARLES J. SCHMIDT,
L. BULLWINKEL.
